UNITED STATES PATENT OFFICE

156,809

DRESS

Main Rousseau Bocher, New York, N. Y., assignor to Passavant Memorial Hospital, Chicago, Ill.,
a nonprofit corporation of Illinois

Application July 28, 1949, Serial No. 4,185

Term of patent 3½ years

(Cl. D3—26)

To all whom it may concern:

Be it known that I, Main Rousseau Bocher, a citizen of the United States, and resident of New York, in the county of New York and State of New York, have invented a new, original, and ornamental Design for a Dress, of which the following is a specification, reference being had to the accompanying drawing, forming a part thereof.

Fig. 1 is a front view of a dress showing my new design.

Fig. 2 is a back view thereof.

I claim:

The ornamental design for a dress, substantially as shown.

MAIN ROUSSEAU BOCHER.
